SHAVING MACHINE

Gustave F. Bahr, Fairfield, Conn., assignor to
Casco Products Corporation, Bridgeport, Conn.,
a corporation of Connecticut

Application April 20, 1938, Serial No. 203,029

6 Claims. (Cl. 30—43)

This invention relates to electric shavers of the type in which there is an outer slotted member and an inner member to shear off hairs projecting through the slots.

In devices of this kind, where the slots extend through a rather sharp corner so as to be partly in the face and partly in the side wall of the device, there is greater opportunity for loose skin, especially the skin on the neck, to enter the slots at this sharp corner and be cut by the inner cutting member. Yet, the providing of the slots so as to be open at both the face and side wall of the outer member permits the cutting of long hairs with greater ease and facility. It also permits tougher and flatter skin portions, as on the cheek and lip of a person, to be shaved more closely.

An object of this invention is to provide an auxiliary guard member for shaving devices of the type referred to, which may be quickly and easily slid over the outer member or head to control the skin in the vicinity of the corner or angle between the face and the side wall of the head. With the improvement of this invention, the neck, underportion of the chin, and other parts having loose skin, may be shaved with the guard in place, and then the guard may be removed to permit close shaving of the tighter and usually tougher portions of the skin.

In the broader aspects of this invention, the auxiliary guard member may lie closely adjacent the corner or angle which it is to shield, and, in fact, may overlie it entirely if desired. Or, the part of the guard member adjacent the corner may be slightly spaced therefrom so as to permit hairs to enter the slots from the side walls but not spaced enough to permit loose skin to extend into the slots.

In the forms of the invention herein illustrated by way of example, the auxiliary guards are applied to an electric shaving device such as is illustrated in my copending application Serial No. 192,765, filed on February 26, 1938. In this device, the head is hollow and circular, and has radial slots in its annular marginal portion continued down through the peripheral wall of the head, and cooperating with the head is a rotary cutting device having shearing edges engaging the head at the interior of both the face and side wall portions.

The auxiliary guards illustrated herein are accordingly ring shape, and are shaped to slidably fit over the peripheral wall of the head where it is held by friction. Part of the aux-

iliary guard is preferably extended beyond adjacent parts so as to facilitate its quick removal.

The present invention also relates to the construction of the head itself, and is concerned with providing for a very thin cutting portion and a strong truss-like central portion. For this purpose, the central portion of the head is made piano-convex so that it gradually thickens from the center outwardly, and preferably the convex side is outside because the slight protuberance formed thereby, when applied to the face, tends to draw the skin inwardly toward the annular slotted marginal portions.

Other features and advantages will herein-after appear.

In the accompanying drawing which illustrates, by way of example, several forms of this invention—

Figure 1 is a top plan view of the head of the shaving device, showing the auxiliary guard member of the present invention in place thereon.

Fig. 2 is a vertical section, showing the relation of the auxiliary guard member to the corner of the head which it is to shield.

Fig. 3 is a sectional view, showing my improved head, having a piano-convex form.

Fig. 4 is a sectional view of a head, and an elevation, in part, of the rotary cutter member, showing a modified form of guard ring wherein the space between the operative surface of the guard ring and a corner of the head is greater than that shown in Fig. 2.

Fig. 5 is a sectional view of a portion of the head with its support and clamping ring, and a portion of the rotary cutter, showing a form of auxiliary guard wherein the guard is made of sheet metal and has a portion projecting beyond the clamping ring to permit the easy removal of the guard.

Fig. 6 is a view similar to Fig. 5, but showing the auxiliary guard member with a portion overlying the corner of the head which it is to shield.

As above stated, the present invention is illustrated as applied to the type of shaving machine disclosed in my copending application Serial No. 192,765, filed February 26, 1938. This shaving machine has a body 10 containing power means, usually in the form of an electric motor, having a drive shaft 11, and at its upper end has a hollow circular casing 12 on which is supported a head 13 having a flange 14 by means of which it is secured to the casing by a flanged ring 15. The head 13 is also hollow and circular, and has a face portion 16 and side wall portions 17. The

annular margin of the face portion 16 is provided with slots 18 arranged radially in the form herein illustrated, and these slots also extend through the adjacent side wall portion 17 of the head.

Within the head and casing there is rotatably mounted a cutter member 19 carried by a sleeve 20 rotatably supported in the casing and driven by the shaft 11. The cutter member 19, in the form shown, comprises a flat strip supported edgewise in slots 21 in the sleeve 20 and extends diametrically across the head and casing. It is urged upwardly by a spring 22 so that its cutting surfaces 23 will engage the interior surface of the slotted portions of the head and cooperate with the walls of the slots 18 to shear off hairs extending through the slots.

In the use of this device, as disclosed in my copending application Serial No. 192,765, filed February 26, 1938, hairs may enter the slots both from the face portion 16 and from the side wall portion 17 as the head is traversed over the surface of the skin to be shaved. The slots in the side wall permit long hairs to enter with great facility, and also permit the hairs on the face, and other parts where the skin is rather tight, to be clipped very short. It may be used with equal facility in shaving the underpart of the chin and the neck where the skin is tender, but the skin should be held taut to prevent loose skin from entering the slots at the corner of the head—that is to say, the place where the portion of the slot which is in the face of the head joins with the portion of the slot which is in the side wall of the head. If reasonable care is exercised in the shaving of the neck with such a device, danger of cutting the skin of the neck is not imminent.

However, to avoid the necessity of using care and of tightening the skin on the neck and other parts where the skin is tender and loose, the present invention provides an auxiliary guard member which may be easily slipped into place when it is desired to shave those parts of the skin and which may be easily removed when shaving the other parts of the skin. Since care and pulling of the flesh and skin is not necessary when the auxiliary guard of the present invention is employed, the shaving operation may be performed much more rapidly and yet a satisfactory shave may be obtained, although, in many instances, the shaving of the tender parts with the auxiliary guard of the present invention will not be quite as close as the shaving of the other parts without the use of the auxiliary guard of this invention.

As shown in Figs. 1, 2 and 3, the auxiliary guard may be in the form of a solid ring 24, the inner surface of which is of such size and shape as to snugly fit over the side walls 17 of the head and substantially cover the side walls. The front surface 25 of the ring is preferably flush with the face 16 of the ring, or at least the slotted portion thereof, so that the ring will not interfere with the operation of pressing the face portion 16 of the head close to the skin to be shaved. If desired, the inner portion of the ring may be slightly chamfered off to provide a bevel 26 which will permit the hairs to stand up and be in position to enter the slots 18 in the face of the head as the head progresses over the skin to be shaved.

With the guard ring 25 in place, the angle formed by the annular marginal portion of the head and the side walls cannot press into the skin and allow loose skin to enter the slots suf-

ficiently to be engaged by the cutter member 19.

In the form of the invention shown in Figs. 1, 2 and 3, it does, however, permit the hairs to enter the slots at the corner between the face 5 and the side walls.

As shown in Fig. 4, the ring 24 may have a wider bevel 27 which may be used by persons whose skin is not quite so tender and loose, or where the person is willing to exercise greater care in shaving the tender parts of the face, and other parts of the body.

In the form of the invention shown in Fig. 5, instead of having it solid, the ring 28 is made of a sheet metal piece having a portion 29 slidably fitting the side walls 17 of the head, and having another portion 30 substantially flush with the face portion 16 of the head. This ring has still another portion in the form of a flange 31 extending beyond the clamping ring 15, so that the guard ring may be easily stripped off the head when it is desired to remove it.

As shown in Fig. 6, the guard ring 32 is also of sheet metal, and has a portion 33 slidably fitting the side walls 17 of the head, but, instead of the upper portion being spaced from the corner of the face and side walls, it has a flange 34 extending inwardly to cover the corner. The guard ring is comparatively thin and lies substantially in the plane of the face 16 of the head, but it positively prevents the slotted corner from being forced into the skin. This form of auxiliary guard may be employed where the skin is so tender that it must not be shaved too closely. The guard ring 32 also has a portion 35 extending beyond the clamping ring 15 so that the guard ring may be easily removed from the head.

In the form of the invention herein disclosed, the ring has a bottom portion 36 adapted to engage the top of the clamping ring 15 to thereby determine the normal position of the guard ring on the head—that is to say, that the outer surface of the guard is in predetermined relation to the face of the cutter. However, if desired, the user may arrange for the outer surface of the ring to project above the face 16 of the head by not pressing the ring all the way on the head.

In my prior application, I have shown the head as in Figs. 1, 2 and 3, so as to have a central depression 37 which may be thicker than the cutting portion 16. According to the present invention, instead of having the central depressed portion 37, the head may have a raised portion 38 shown in Fig. 3. This raised portion is preferably convex so as to press into the skin and flesh as the razor is traversed across the surface being shaved. It is also preferably thicker at the center than it is at the edges so as to give strength and rigidity to the head, and, as shown, it may be plain convex, having a flat inner surface 39. In this case, so as to avoid the frictional contact of the entire movable blade with the head, the blade 40 has a central concave portion 41.

Variations and modifications may be made within the scope of this invention and portions of the improvements may be used without others.

I claim:

1. A shaving machine for personal use comprising a hollow circular head having closely spaced narrow radial hair-receiving slots in the annular marginal and peripheral wall portions thereof; a support for said head having a threaded portion and a flat end surface for engaging the inner end of the head; a flange on the head; a clamping ring threaded on said support and

having a flange to engage the flange on the head and secure the head to the support; a rotary cutter mounted within said support and head and having shearing edges cooperating with the interior edges of the walls of said slots in the annular marginal and peripheral wall portions of the head to shear off hairs extending therethrough; and a guard ring slidably mounted on the peripheral wall of the head and having an inner portion engaging said clamping ring to position the same on said peripheral wall, said guard ring having an outer portion located closely adjacent the junction of the face and the slotted peripheral wall of the head to prevent loose skin from extending into the portions of the slots in the peripheral wall of the head.

2. A shaving machine for personal use comprising a hollow circular head having closely spaced narrow radial hair-receiving slots in the annular marginal and peripheral wall portions thereof; a support for said head having a threaded portion and a flat end surface for engaging the inner end of the head; a flange on the head; a clamping ring threaded on said support and having a flange to engage the flange on the head and secure the head to the support; a rotary cutter mounted within said support and head and having shearing edges cooperating with the interior edges of the walls of said slots in the annular marginal and peripheral wall portions of the head to shear off hairs extending therethrough; and a guard ring slidably mounted on the peripheral wall of the head and having an inner portion engaging said clamping ring and an outer portion located closely adjacent the junction of the slotted annular and marginal peripheral wall portions of the head to prevent loose skin from extending into the portions of the slots in the peripheral wall of the head, said guard ring having a projecting flange by means of which it may be manually slid on and off the head.

3. A shaving machine for personal use comprising a hollow circular head having closely spaced narrow radial hair-receiving slots in the annular marginal and peripheral wall portions thereof; a support for said head having a threaded portion and a flat end surface for engaging the inner end of the head; a flange on the head; a clamping ring threaded on said support and having a flange to engage the flange on the head and secure the head to the support; a rotary cutter mounted within said support and head and having shearing edges cooperating with the interior edges of the walls of said slots in the annular marginal and peripheral wall portions of the head to shear off hairs extending therethrough; and a guard ring slidably mounted on the peripheral wall of the head and having an inner portion engaging said clamping ring and an outer portion located closely adjacent the junction of the slotted annular and marginal peripheral wall portions of the head to prevent loose skin from extending into the portions of the slots in the peripheral wall of the head, said guard ring having a projecting flange by means of which it may be manually slid on and off the head.

4. A shaving machine for personal use comprising a hollow circular head having closely spaced narrow radial hair-receiving slots in the

annular marginal and peripheral wall portions thereof; a support for said head having a threaded portion and a flat end surface for engaging the inner end of the head; a flange on the head; a clamping ring threaded on said support and having a flange to engage the flange on the head and secure the head to the support; a rotary cutter mounted within said support and head and having shearing edges cooperating with the interior edges of the walls of said slots in the annular marginal and peripheral wall portions of the head to shear off hairs extending therethrough; and a guard ring slidably mounted on the peripheral wall of the head and having an inner portion engaging said clamping ring and an outer portion located closely adjacent the junction of the slotted annular and marginal peripheral wall portions of the head to prevent loose skin from extending into the portions of the slots in the peripheral wall of the head, said guard ring at its inner end having a projecting flange by means of which it may be manually slid on and off the head.

5. A shaving machine for personal use comprising a hollow circular head having closely spaced narrow radial hair-receiving slots in the annular marginal and peripheral wall portions thereof; a support for said head having a threaded portion and a flat end surface for engaging the inner end of the head; a flange on the head; a clamping ring threaded on said support and having a flange to engage the flange on the head and secure the head to the support; a rotary cutter mounted within said support and head and having shearing edges cooperating with the interior edges of the walls of said slots in the annular marginal and peripheral wall portions of the head to shear off hairs extending therethrough; and a guard ring slidably mounted on the peripheral wall of the head, said ring having a portion engaging said clamping ring when mounted on said wall to position a portion thereof so as to lie substantially flush with the face of the head and closely adjacent the slotted peripheral wall thereof to prevent loose skin from extending into the portions of the slots in the peripheral wall of the head.

6. A shaving machine for personal use comprising a hollow circular head having closely spaced narrow radial hair-receiving slots in the annular marginal and peripheral wall portions thereof; a support for said head having a threaded portion and a flat end surface for engaging the inner end of the head; a flange on the head; a clamping ring threaded on said support and having a flange to engage the flange on the head and secure the head to the support; a rotary cutter mounted within said support and head and having shearing edges cooperating with the interior edges of the walls of said slots in the annular marginal and peripheral wall portions of the head to shear off hairs extending therethrough; and a guard ring slidably mounted on the peripheral wall of the head and having an inner portion engaging said clamping ring and an outer portion overlying the junction of the face and the slotted peripheral wall of the head to prevent loose skin from extending into the portions of the slot in the peripheral wall of the head.
